UPHOLSTERED CHAIR

Donovan R. Beachley, Hagerstown, Md., assignor
to Beachley-Reichard Furniture Co., Inc.,
Hagerstown, Md., a corporation of Maryland

Application September 15, 1942, Serial No. 458,363

1. Claim. (Cl. 155—179)

This invention relates to improvements in upholstered furniture, such as chairs, davenport's and the like, and more particularly to improvements in the construction of spring cushion bottoms and backs for such furniture, as is embodied in the present application.

Upholstered chairs as at present constructed usually embody a deep spring cushion seat and back structure which is set into the frame of the chairs and covered by a base fabric and suitable stuffing or padding and this filling material is in turn covered by suitable ornamental fabric to provide the desired finish for the chairs. While these spring cushion structures take many forms, they usually embody arrangements of coiled metallic springs, spring wire frames, or a combination of the two which from the standpoint of comfort and durability have been generally satisfactory.

At the present time, however, the use of metal is highly restricted and in order to continue the production of this same grade of highly desirable spring cushion upholstered furniture, recourse must be made to the use of available substitutes which has necessitated reconstruction of the chair as a whole.

Wherever the term chair is used herein, it will be understood that other types of spring cushion upholstered furniture, such as davenport's, etc., are intended to be covered thereby.

It is recognized that prior to the age of the more modern upholstered chair that wooden slats, in many forms, were used in bed bottoms as a support for the readily removable mattress, and that in some instances even in chair bottoms, but that this latter use did not become highly developed due to the rapid developments then being made in the metallic spring arts which were more suitable for the spring cushion support of upholstered chair bottoms and backs, as a unitary structure. Hence, when confronted with the problem of substituting a material for metal in the spring cushion support of upholstered chairs, there is no teaching in the prior art of suitable and reliable constructions which are equal to metallic spring cushions from the standpoint of comfort and durability as well as from the standpoint of economical manufacture and sales appeal in upholstered chairs.

It is accordingly the object of this invention to provide a non-metallic spring cushion construction in upholstered chairs which provides the required cushion depth of upholstery support as well as comfort, durability in use and

ease of manufacture heretofore provided by metallic spring construction.

Another object of the invention is the provision of a wooden spring slat cushion in upholstered chairs which is economical to manufacture, highly efficient in use, durable and silent in action and which due to the minimum bending action required of each slat element of the assembly for a given deflection of the upholstery, is not subject to local unevenness and breakage with consequent shifting and rupturing of the stuffing and covering fabric of the chair.

A further object of the improved spring cushion upholstery support for upholstered chairs is to prevent the formation of ridges and other unevenness in appearance and use such as has heretofore been common to upholstered chairs employing many types of metallic spring constructions.

A still further object of the invention is the provision of a non-metallic spring cushion structure in an upholstered chair which is light in weight, simple in construction and which is capable of manufacture at relatively low cost.

For a more complete understanding of the nature and objects of the invention, reference will be had to the following detailed descriptions, taken in connection with the accompanying drawings, wherein—

Fig. 1 is a perspective view, partially broken away and in section, of a chair disclosing the application of the present invention in accordance with a preferred embodiment thereof;

Fig. 2 is a vertical sectional view of the chair illustrated in Fig. 1, the section being taken in a plane intermediate of and parallel with the arms of the chair illustrating the normal cushion support of the upholstery;

Fig. 3 is a horizontal section in a plane generally represented by line 3—3 in Fig. 2;

Fig. 4 is a vertical sectional view in a plane generally represented by line 4—4 in Fig. 2;

Fig. 5 is an enlarged view of a portion of the structure illustrated in Fig. 2; and,

Fig. 6 is a perspective view of one end of a spring cushion slat element.

Referring now to the drawings, "C" designates an upholstered chair in its entirety embodying my invention and while a specific form of chair is disclosed, it is to be understood from the foregoing that the present invention is not limited thereto but is adapted for use in upholstered chairs of various other structural forms and shapes.

The chair C, therefore, may comprise a rec-

tangular seat frame 10 which includes a front rail 11, side rails 12, and a rear rail 13, the side and rear rails at their adjacent ends being connected by a pair of upright back supports 14. These supports are shown interconnected by upper and lower rails 15 and 16, respectively.

The chair further comprises legs 17, the pair at each side of the chair being interconnected by a rail 18 suitably secured to rail 12. Each such pair of legs at their upper ends supports an arm 19 from the rear portion of which up-stands a back edge shaping frame member 20, which is suitably secured to the adjacent support 14.

While the parts just enumerated are generally present in the frame construction of all upholstered chairs, each of these parts has been made to cooperate in one way or another with the parts now to be described to provide the non-metallic spring cushion upholstery support of the present invention.

The present invention, therefore, pertains to the spring cushion construction in the seat and back of an upholstered chair, and by way of illustration the seat construction embodies in its preferred form the following structure:

Suitably secured to the inner faces of each of the front and rear rails 11 and 13 of the seat frame 10 are a plurality of uniformly spaced and vertically disposed blocks 21 to the upper and lower ends of which are secured strips 22 and 23, respectively, thereby defining opposed sets of horizontally spaced vertical recesses 24 which are closed at their upper and lower ends. A plurality of sets of vertically coacting independently yieldable bowed wood spring slats is freely supported by the frame 10 and each set is vertically aligned with and guided by each opposed pair of recesses 24, and is independent of adjacent sets.

As illustrated, each set of spring slat members comprises an upwardly bowed bottom slat member 25, an intermediate downwardly bowed slat member 26 and an upwardly bowed slat member 27. The slat members 25 and 26 may be suitably connected at 28 at the adjacent contacting crown portions and the opposite ends of the lower slat members 25 are normally rested freely on the strips 23 at the lower ends of the recesses 24, laterally spaced from the rails 11 and 13, which form the bases of the recesses 24. The ends of slat member 27 are freely rested on the opposed ends of slat members 26, within the guiding and spacing slots 24, where the end portions of the slat members 26 and 27 are confined by the top strips 22 against further upward movement.

As shown in Fig. 2, the ends of the slat members are all normally spaced from the rails 11 and 13 within the slots 24 to provide for expansion or straightening of the slat members upon compression or downward deflection of the upholstery in normal use.

In this connection, it will be noted that due to the combination and arrangement of freely moving, independently acting bowed slat members 25, 26 and 27, only partial straightening of each of the slats follows the maximum deflection or depression of the upholstered seat support between the rails of frame member 10 in use. By this construction of spring cushion support for upholstered chairs, an extremely deep, soft and uniform action is provided with the minimum of wear and strain on the supporting parts.

While the spring slat members 25, 26 and 27 fit within the vertically extending recesses 24 with sufficient looseness to afford proper move-

ment of the ends of the slat members therein, it is to be particularly noted that these end portions of these slat members are squarely supported and laterally braced by the sides of the blocks 21, as well as by the tensioned base fabric 36 of the upholstered supporting member, to preclude tilting of the individual slat members of the assemblies, as shown in Figs. 2 and 4.

Further, by the provision of three oppositely bowed spring slat members in each assembly or unit, as shown, a relatively heavy weight is capable of being sustained in normal fashion by the upholstery supports 36, 37 and 38 by the use of relatively narrow and light weight wooden slat members having a relatively high degree of flexibility and resistance to atmospheric changes.

As a further means of insuring freedom in upholstery support deflection with the minimum of noise in use, and variance in tension under changing atmospheric or climatic conditions, the ends of the slat members are shown rounded to reduce friction with the end rails 11 and 13 and the entire bodies of the slats are coated or encased in a covering of lacquer or other smooth and flexible moisture resisting material, as shown at 30 in Fig. 6.

While the foregoing has described the construction and operation of the upholstered spring cushion support as being the seat, it will be understood that the spring cushion back of the upholstered chair may take the same form.

Where less deflection but soft action is required, however, a single bow arrangement may be employed such as is illustrated in the accompanying drawings. In this arrangement, like that previously described, the back spring cushion comprises upper and lower strips 31 and 32 secured to rails 15 and 16 and provided with horizontally spaced aligned facing recesses 33 in which are received the opposite ends of bowed slat members 34. The ends of these members 34 are normally spaced from the bottoms of the recesses for expansion or straightening of the slat members as is clearly indicated in Fig. 5, and as was described more or less generally in connection with the chair seat. The ends of these slat members 34 are also preferably rounded transversely of the members and their bodies coated to reduce friction and resist changes in weather conditions, all as was above described, and illustrated in Fig. 6.

While the back slat members are shown as wider and fewer in number than the seat slat members, it is to be understood that the number and width of the spring slats in either the seat or back may be varied to meet requirements in cushion depth and style of the upholstered chair to be produced.

Various forms and arrangement of padding and base covering fabrics may be applied to the seat and back spring cushion members above described and one suitable form is illustrated in Fig. 1 and Fig. 2. This form comprises a suitable base fabric 36 which rests directly on and slightly compresses the bowed surface of the uppermost series of slat members 27-34, see Fig. 2. A suitable thickness of padding 37 and then a suitable finishing or covering fabric 38 are secured over the base fabric between the rails of the seat and back frames and together provide an upholstered supporting member. The base fabric 36 preferably terminates in a cushion edge roll 39 resting on the upper edge of the front rail 11, as is illustrated in Fig. 1, to cushion the front edge of the seat frame 10 and also to

suitably space the base and covering fabrics for proper cushioning support by the coacting spring cushion members.

From the foregoing disclosure, it will be appreciated that the present invention provides an all-wood spring cushion and frame construction for upholstered chairs which is highly efficient in operation and durable and which is capable of manufacture at relatively low cost.

It is to be further noted that the wood slat members have been constructed and arranged so that they will readily flex without danger of impairment even after a relatively long period of use, whereby the cushion will not only maintain its shape and effectiveness but there will be little likelihood of breakage with consequent rupture of the padding as well as discomfort to a user.

While I have disclosed but a single specific embodiment of the invention, such is to be considered as illustrative only, and not restrictive, the scope of the invention being defined in the appended claim.

What I claim and desire to secure by United States Letters Patent therefore is:

A seat cushion construction for upholstered chairs comprising a rigid rectangular base frame, 5 horizontally spaced vertical recesses in each of two opposed sides of the frame with the recesses at each side being closed at their lower ends and aligned, and opening toward the recesses at the opposite side, a plurality of pairs of yieldable bowed wood slats having their opposite ends freely disposed in each two aligned recesses, said pairs of slats being in supporting engagement with the upholstery of the chair, each pair of slats being oppositely bowed and having their 10 ends freely slidable relative to each other, and a plurality of additional wood slats each bowed convexly to one of the pairs of slats and connected thereto intermediate the ends thereof, said additional wood slats being supported at 15 their ends on the closed ends of the recesses.

DONOVAN R. BEACHLEY.
